UNITED STATES PATENT OFFICE

HENRY W. GRIMM, OF MOLINE, ILLINOIS

METHOD FOR TIMING TOLL TELEPHONE CIRCUITS

Application filed May 13, 1929. Serial No. 362,693.

The invention has reference to a method for timing toll telephone circuits, and relates to certain systems, methods, and apparatus used to determine the intervals of time during which the telephone circuits are used, in telephone exchange systems in which a toll or charge, computed on a basis of time periods or intervals, is made by the operators to the subscribers or users, for the use of interconnected telephone circuits, employing link circuits or otherwise. Under the present arrangement and manner of conducting the toll circuits there is no adequate means for appraising the user of the system of the time when the charge period starts, when certain graduated divisions of such period terminate, and when the full period of time has closed, or is about to close. The present methods made use of by the toll operators are also crude and unreliable.

The chief purpose of this invention is to provide systems, methods and apparatus to substantially simultaneously notify both the operator and the user of the telephone toll circuits of the beginning, end, divisions, and multiples of the predetermined periods of time, as they are being measured, determined, registered, and recorded for the purpose of computing the charges for the use of the telephone circuits, and thus provide improved service as compared with the service possible in systems where only the operator obtains this information.

Another purpose of the invention is to provide a warning signal for the benefit of the user a brief interval prior to the closing of the toll period, to warn him that the time will soon expire.

The above named and other features and advantages of the invention will more fully appear from the following specification, reference being had to the accompanying drawings, which are all of a diagrammatic character, and in which the same reference characters are employed to designate similar parts throughout.

In said drawings:

Fig. 1 illustrates the system in one of its simplest and most basic embodiments.

Fig. 2 is a similar view of a modified construction and arrangement thereof.

Fig. 3 shows a still different arrangement thereof.

Calling attention first to Fig. 1 of the drawings, the reference numbers 1 and 2 indicate two subscriber's stations wired in system in the usual manner, said stations being shown at one side of a broken line 3, while on the other side of said line is indicated a central office equipment including a battery 4 which provides the usual talking current for the system, thru a retardation coil 5. All of the apparatus of the system is of the usual type, and only sufficient portions thereof are shown in the drawings, to properly illustrate the invention.

A shaft A is continuously rotated at predetermined speed in the direction indicated by the arrow, by a suitable time measuring device, not shown in the drawings. A point indicator B is attached to the shaft A by suitable friction or other means which causes said indicator to rotate with and at the same speed as the shaft at such times as the movement is not interfered with. Said indicator is held normally, however, in a given position by means of a pin H inserted in the path of the indicator, and acting as a stop therefor. Other means can be substituted for that shown, or the indicator can be held manually from operation. Upon being released the indicator makes a complete revolution with the shaft A during a predetermined period of time.

C indicates a stationary dial, around which the indicator B rotates, said dial being provided with graduated markings at D, E, F, and G. The stop H, which is of a suitable type to be manually released or reset, holds the indicator stationary at a position on the dial C, near, and counter-clockwise to the marking D.

Supported in proximity to the indicator B is a bell-crank lever formed of a short arm I and long flexible arm I², with a pivotal point at I¹. The arm I is in the line of rotation of the indicator B, which moves the arm momentarily upwards in its movement beneath the same. This also elevates the arm

I^2 and hammer J on the end thereof, such arm and hammer dropping again as the indicator passes the end of the arm I . The downward movement is arrested by a stop 13 , while the hammer continues downwardly until it encounters a bell K just below the same, ringing said bell. This all takes place as the indicator is passing the point D on the dial. A telephone transmitter L is supported in proximity to the bell K , and is electrically connected with the telephone circuit, as indicated at M and N . The relative positions of the bell and transmitter are such that the audible vibrations from the bell effectively reach the transmitter and cause the same to function, thus varying the current in the telephone circuit, which variations substantially simultaneously produce corresponding audible vibrations in the receivers of the telephone circuit.

It is thought that the following description of the operation of the system and apparatus shown in Fig. 1 will give a better understanding of the invention. When the operator releases the stop H , the indicator B starts to rotate with the shaft A , and with the speed of said shaft. Immediately after starting, the indicator momentarily lifts the hammer J by engaging with the trip lever I . The hammer J falls and strikes the bell K as the indicator B is at the point D in its rotation, causing the bell K to vibrate audibly. This audible signal notifies the operator of the beginning of a predetermined interval of time, which will end after the indicator B has made one full revolution, at which instant the operation which produced the first signal will have been repeated, causing a second signal which notifies the operator of the ending of the interval of time. Substantially simultaneously with the first and second signals for the operator, respectively corresponding audible signals for the users of the telephone circuit are produced in the receivers at stations 1 and 2 , caused by the audible vibrations of the first and second signals for the operator, respectively from K , reaching and causing the transmitter L , electrically connected with the telephone circuit, to function and thus vary the current in the telephone circuit. As the indicator B continues to rotate, in a similar manner similar time intervals will be measured with each full rotation, and a similar signal for the operator, together with a corresponding signal for the users, synchronized with each other, will in like manner be given at the end of each time interval measured, which will also serve as a signal for the beginning of the next time period.

As shown in Fig. 2, an electrically operated means for signalling the operator is substituted for the mechanically operated signalling means shown in Fig. 1. A terminal connection O is so placed on the dial C that

the yielding flexible tip P of the indicator B in its rotation momentarily makes electrical contact with O at the position D , simultaneously closing a circuit extending from a battery Q through a brush R , slip-ring S suitably mounted on the pointer B , indicator B , tip P , contact O , and lamp T to the battery Q , and circuit extending from a battery U through a brush V , ring S , pointer B , tip P , and contact O through the telephone circuit to battery U . The momentary closing of said circuits gives to the operator a visible signal by lighting the lamp T , and to the users a corresponding signal, substantially synchronized with the operator's signal, by varying the current in the telephone circuit by the voltage momentarily impressed on it from the battery U .

As shown in Fig. 3, a telephone receiver W in the same circuit with the lamp T provides a means to signal the operator audibly. An electrically operated bell X in the circuit extending from the battery U acts in conjunction with the transmitter L to vary the current in the telephone circuit in a similar manner to the mechanically operated bell in Fig. 1. Terminal contacts Y and Y^1 mounted in a similar manner to the contact O at positions near each other on the dial C counter clockwise to the marking D , are both electrically connected to both of the circuits extending from the batteries Q and U . The indicator B after passing the point D in any full rotation momentarily closes both of said circuits simultaneously, first by making contact with Y and again by making contact with Y^1 , thus providing means for substantially simultaneously giving a signal to both operator and users, which may be differentiated from that made when the indicator B makes a contact with terminal O , and which may serve as a warning signal to the operator and users to get ready to carry out possible predetermined procedures at the end of the interval of time which will end with the signal given when the rotary movement of the indicator causes it to again make contact with terminal O .

While I have purposely chosen to show this invention in its most simple and basic embodiments in order that it may be more easily and clearly understood, I do not desire to limit myself to them, but may employ any of the possible various modifications and elaborations in the details of construction and arrangements of circuits and parts which do not depart from the spirit of my invention and are restricted only by the scope of the following claims, many of which will be obvious to those skilled in the art, and several of which follow:

The indicator B may be associated and interconnected with a suitable registering device for registering the number of full and fractional revolutions it makes after the stop

H is released. Said indicator and such registering device may be associated and interconnected with a suitable recording device to record the registrations. Suitable means 5 may be employed to instantly return the indicator, the registering device, and the recording device to a starting position. The indicator B, the registering device and the recording device may be associated and interconnected 10 with a suitable time indicating device, such as a clock, to show the relation of the time intervals to the time of day.

I may employ any suitable type of time interval measuring, indicating, registering and recording means, any suitable electrically or magnetically operated stop release in place of the manually operated release described for actuating the stop H, and any other suitable means for varying the current in the telephone circuit to produce the audible signals in the receivers.

While the means employed to vary the current in the telephone circuit is shown connected directly to such circuit at M and N, 25 said means may be connected to said circuit by any other suitable means such as by induction, a link circuit, a telephone jack and plug, or suitable off and on switch.

Any number of terminal contacts similar 30 to that shown at O and similarly placed on other positions on the dial C, such as at E, F, and G, and similarly connected to the circuits, may be employed to give signals corresponding to predetermined divisions of 35 the interval of time measured by a full revolution of the indicator B. These contact terminals may vary as to size of contact surfaces and may be grouped to give several types of signals which can be identified one 40 from the other. The terminal contacts may be so mounted as to be adjustable to different operable positions necessary to make contact with the indicator B by suitable means actuated by said indicator and the shaft A 45 in their rotation, to give a different type of signal as the indicator passes a given position on the dial C in successive rotations. Various numbers of telephone receivers may be in the telephone circuit, each providing 50 the audible signals impressed upon the telephone circuit.

Any other suitable current supply may be substituted for the battery U in Fig. 2, such as A. C. current of any frequency within the 55 audible range, to produce signals in the receivers of desired pitch. Any other suitable electrically actuated sound producing device may be substituted for the bell X shown in Fig. 3.

Combination wire and wireless telephone 60 circuits may be used as well as the wire telephone circuits shown. Operator controlled means may be associated and inter-connected with the indicator B to hold the same stationary for periods at any position on the

dial C after the indicator starts to rotate from the starting position D, thus increasing the interval of time taken by the indicator to make a full revolution when thus held, substantially by the length of time such indicator is held, thus providing a means for subtracting from the time interval a telephone circuit is used, any periods of inoperable interference in the telephone circuit. Means 70 may be provided to give the users an identifiable audible signal in the receivers during 75 the periods when the indicator is held.

The audible signals in the receivers may be of such a nature in respect to their duration, volume, and musical pitch as to cause 80 negligible interference with the conversation and yet be distinct.

Several of the devices described may be built into one unit, being actuated by the same time measuring means, with which unit 85 one or more operators may time and signal several circuits simultaneously.

What I claim, and desire to secure by Letters Patent, is:

1. In combination with a telephone system 90 including subscribers, stations and lines; a member movable continuously at a predetermined rate of speed, an element mounted on said member for movement by the latter, releasable means for holding said element normally against movement during movement of said member, said means being adapted for release to enable said element to move with said member when a circuit is established between a pair of subscribers' stations in the 95 telephone system and when conversation begins, and means operable by movement of said element to effect signal variations in the current of the subscriber's line at predetermined intervals of 100 time.

2. In combination with a telephone system including subscribers' stations, lines and a central operator's station; an element normally held against movement and movable at a predetermined rate of speed when released, releasable means holding said element normally against movement, said means being adapted for release by the central station operator when an operative circuit has 110 been established between a pair of stations in the telephone system, and means under the control of said first named means operable immediately following release thereof to simultaneously effect an indication for the operator and a signal variation in the current of said circuit and thereafter to simultaneously repeat said indication and said signal variation following the elapse of 115 predetermined periods of time.

3. In combination with a telephone system including subscribers' stations and lines; an element normally held against movement and movable at a predetermined rate of speed when released, releasable means holding said 120

element normally against movement, said means being adapted for release when an operative circuit has been established between a pair of stations in the telephone system, and
15 means under the control of said first named means operable immediately following release thereof to produce a signal variation in the current of said circuit and thereafter to repeat said signal variation following the
19 elapse of predetermined periods of time.

4. In combination with a telephone system including subscribers' stations and lines; an element normally held against movement and movable at a predetermined rate of speed
15 when released, releasable means holding said element normally against movement, said means being adapted for release when an operative circuit has been established between a pair of stations in the telephone system, a sound producing device, means under the control of said first named means operable immediately following release thereof to cause said device to produce sound and thereafter to repeat said sound following
20 the elapse of predetermined periods of time, and a transmitter located adjacent to said sound producing device and connected with the subscriber's line.

5. In combination with a telephone system
30 including a subscriber's line; a shaft rotatable constantly at a fixed rate of speed, an element having a slip connection with said shaft, a releasable stop to hold said element against rotation, said element being adapted
35 to rotate with said shaft when said stop is released, and means operable by said element immediately following its release to effect a signal variation in the current of said subscriber's line and thereafter to repeat said
40 signal variation following the elapse of predetermined periods of time.

6. In combination with a telephone system including subscribers' stations, lines and a central operator's station; means for use by
45 the central station operator to determine a period of use of an operative circuit between a pair of stations in the telephone system, and means under the control of said first named means to effect a signal variation in
50 the current of said circuit at the beginning of said period and to repeat said signal variation following the elapse of predetermined periods of time.

7. In combination with a telephone system
55 including subscribers' stations, lines and a central operator's station; indicating means operable by the central station operator to determine a period of use of an operative circuit between a pair of stations in the telephone system, and means under the control of said first named means to effect and repeat
60 signal variations periodically in the current of said circuit, synchronized with the indications of said indicating means.

65 8. In combination with a telephone system

including subscribers' stations, lines and a central operator's station; means to indicate to the operator a period of use of an operative circuit between a pair of stations in the telephone system, and means under the control
70 of said first named means to effect and repeat signal variations periodically in the current of said circuit, synchronized with the indications of said first named means.

In testimony whereof I affix my signature. 75
HENRY W. GRIMM.
